INSOLE

Henry Lipton, Chicago, Ill., assignor to J. P. Smith Shoe Company, Chicago, Ill., a corporation of Illinois

Application June 22, 1949, Serial No. 100,580

2 Claims. (Cl. 36—22)

1 This invention relates to improvements in shoe construction and particularly to the construction of insoles that are provided with sewing lips.

In the manufacture of shoes it has become common to make insoles having sole pieces of thin leather to avoid substantial increase in the stiffness of the shoe sole over that resulting primarily from the thickness or character of the material of the outsole itself. Such thin leather sole pieces of the insoles generally are formed of upper leather or even of thinner stock and hence are too thin to be channelled to provide sewing lips to which the uppers and welts are attached. The lip of the flexible sole pieces of some such insoles are of the type shown in the De Vito et al. Patent No. 2,206,716 granted July 2, 1940 and are formed of thin flexible strips of leather cemented to the lower surface of the sole pieces and each to the other and constitute, in effect, continuations of the lips formed by channelling the thicker shanks of the insoles in the manufacture of full welt shoes.

It is an object of the present invention to provide an improved insole for either full or half welt shoes, the flexible sole piece of which insole is provided with lip strips of thin flexible material attached to the insole and one of which forms, in effect, a binding for the edge of the sole piece for preventing the edge from coming loose from the strips and curling up or forming wrinkles which may produce discomfort to the wearer as has sometimes occurred where as heretofore the lip strips have been attached to the lower side of the sole pieces only.

In the accompanying drawings which show structure illustrative of the invention,

Figure 1 is a perspective view of an insole for a full welt shoe, the insole shown having the lip strip incompletely formed;

Fig. 2 is an enlarged sectional view taken on line 2—2 of Fig. 1;

Fig. 3 shows the upper lip strip of Figs. 1 and 2 drawn around the edge of the insole into contact with a lip strip on the lower surface of the sole piece;

Fig. 4 is a transverse sectional view through a side portion of a shoe and insole after the upper and the welt have been attached to the lip shown in Fig. 3;

Fig. 5 is a sectional view, similar to that shown in Fig. 4, after the lip has been trimmed and leveled, cushioning material inserted and the outsole attached.

Referring to Fig. 1, an insole is shown pro-

vided with a heel and shank portion 10, and since the particular insole illustrated is for use in a full welt construction, the shank is channelled to provide a lip 11 which at its forward end is joined, as by cement, to the adjacent ends of the lip strips of the sole piece 12 after the latter have been completely formed. The forward end of the shank is skived or beveled at the lower side thereof while to the upper side is cemented the rear end portion of a beveled end of the sole piece 12 which is of thin flexible material, such as shoe upper material or thinner stock. Generally a piece of canvas or like fabric 13 is cemented to the lower surface of the sole piece. A representation of the edge of the fabric 13 has been omitted from Fig. 1 of the drawing because of the small scale of the latter but is shown in the remaining figures.

To the lower surface of the sole piece 12 is attached a lip strip 14 of relatively thin material such as kid, the strip being provided with an outwardly turned flange 14a which, in the manufacture of the insole, is initially cemented to the sole piece along the outer edge thereof. The body 14b of the strip extends generally outward or at right angles to the plane of the sole piece. A second lip strip 15 of similar thin flexible material is employed in forming the composite lip but instead of being secured to the lower face of the sole piece 12, as has heretofore been the general practice, it is attached to the opposite or upper surface of the sole piece. This lip strip 15 as shown in Fig. 1 extends along the edge of the sole piece similarly to the strip 13 and has a flange 15a extending outwardly that preferably is stitched to the sole piece by a line of stitches 16. Cement may be used also in securing the flange 14a to the insole. The stitches, as shown in Fig. 1 extend through the flange 14a also and thus securely attach the strips to the sole piece along the edge thereof.

For the purpose of providing a smooth joint at the junction of the sole piece and the upper portion of the lip strip 14 when the formation of the lip has been completed, a groove or rabbet 17 preferably is formed in the margin of the upper surface of the sole piece 12, of the width of the flange 15a and in which the flange is seated. The depth of the groove preferably is such as to accommodate the double thickness of the strip 15 after the latter has been folded over the edge of the sole piece and flattened down or leveled. In Fig. 3 the strip 15 is shown in the relation just mentioned, that is, it has been turned outwardly and downwardly over the edge of the sole

piece 12, thence inwardly over the flange 14a and brought into face to face contact with the body 14b of strip 14 to which it is cemented. The rear ends of the two strips are likewise cemented to opposite sides of the respective channel lips 11 formed in the shank to provide a continuous securing lip extending along opposed sides of the shank and along the edge of the sole piece. Where an improved insole is to be made for a half welt shoe, the lip 11 of the shank is omitted and the sole piece only is provided with a sewing lip, made as above described.

The composite lip shown in Fig. 3 formed by the bodies of the two strips 14 and 15 and designated generally by numeral 18 is firmly secured to the edge of the insole piece 12, the edge of the latter being enclosed by the strip 15 as shown. Hence in the completed shoe the edge of the sole piece is held down firmly by the composite strip, particularly by the strip 15 which is attached to the upper surface of the sole piece and which, by reason of the construction shown, when flattened or leveled lies in the plane of the upper surface of the sole piece.

In use of an insole, made in accordance with the foregoing description, it is first tacked to a last. An upper 19 is then secured, as by staples or the like temporary fastening means (not shown) to the composite lip 18 of the insole. A welt 20, beveled at the inner upper edge as shown in Fig. 4 and provided with a securing groove 21 is then, by stitches 27 secured in place, the stitches passing through the composite lip 18 and the overlapping portion of the upper 19. After trimming the edges of the lip and upper close to the line of stitches 27, leveling the same and inserting suitable cushioning material 23, such as cork, felt or the like, an out sole 24 is secured to the welt by stitches 25. The shoe is subsequently completed by conventional or well-known manufacturing steps.

The improved insole, as stated above, has its edges firmly bound, by the lip strip construction described and is retained by the binding against loosening or wrinkling at the edge and thus upward curling that produce ridges which impair the comfort of the shoe.

While I have shown the improvements in the presently preferred form, various changes may be made therein within the spirit of the invention defined by the following claims.

I claim:

1. A flexible sole piece for an insole provided with a lip strip having a flange contacting the lower surface of the sole piece along the margin thereof and provided with a downwardly extending body spaced inwardly from the edge of the sole piece, and a second lip strip provided with a flange disposed on the upper side of the sole piece along the edge thereof, said flanges being secured to the sole piece by a line of stitches common to the flanges, said second lip strip having a body portion extending from the inner edge of the respective flange and extending outwardly over the latter and downwardly over the edge of the sole piece and inwardly and again downwardly into parallelism and contact with the body of the other strip to provide a sewing lip of double thickness.
2. A flexible sole piece for a shoe insole provided with a lip strip on the lower surface thereof, said strip comprising a flange secured to said surface and a downwardly projecting body portion, the marginal portion of the upper surface of the sole piece being provided with a rabbet of a depth corresponding approximately to twice the thickness of the material of a second lip strip, and a second lip strip provided with a flange secured in said rabbet and a body portion extending over said flange in the plane of the upper surface of the sole piece and downwardly over the edge of the sole piece and into face to face contact with and secured to said downwardly projecting body of the first strip to provide a sewing lip of double thickness projecting from the lower surface of the sole piece.

HENRY LIPTON.
